ARMCHAIR WITH TABLE ATTACHMENT

Elsie M. Runkles, Detroit, Mich.

Application August 20, 1949, Serial No. 111,395

8 Claims. (Cl. 155—188)

1

This invention relates to arm chairs having table or desk attachments, and may be considered an improvement on the disclosures of Patents 1,803,947 and 1,891,691, issued respectively May 5, 1931 and December 20, 1932.

An object of the invention is to provide in an improved manner for hinging one end of a table member to a support and for adapting such member and support to be slid into and from a compartment provided in one of the arm-forming side members of a chair, whereby said member may be swung after withdrawal from the compartment from its vertical position admitting it to and from the compartment to a horizontal position of use.

Another object is to provide an improved support normally housed in a compartment formed in the other of said arm-forming side members and slideable forwardly to serve as a seat for the free end portion of the table member.

Another object is to form the last-mentioned support with one or more recesses for articles, and to render such recesses accessible by forwardly actuating such support to its seating position for the table member.

Another object is to adapt the table member to be swung laterally while maintaining its horizontal position, so that an occupant of the chair may leave the same without necessity of first unloading the table member.

Another object is to horizontally hinge one end portion of a table member to a forward extension from a support retained within a compartment formed in one of the arm-forming side members of a chair, and to provide a support for the other end portion of the table member on the other of said side members, and to vertically pivot said extension on the corresponding support so that the table member, as disposed for use, may be swung laterally in unison with said extension to allow ingress and egress to and from the chair, and to equip the extension with an auxiliary support for the table member, safeguarding the latter from collapse when so swung.

These and various other objects are attained by the construction hereinafter described and illustrated in the accompanying drawings, wherein:

Fig. 1 is a perspective view of my improved chair, showing its table member and the two supports for such member withdrawn from their compartments, preliminary to upward swinging of said member to its use position.

Fig. 2 is a top plan view of the chair, showing in full lines the normal use position of the table

member and in dash lines a laterally swung use position.

Fig. 3 is a side elevational view, corresponding to the full line showing of Fig. 2.

Fig. 4 is a fragmentary vertical sectional view of the table member and one of its supports, taken on the line 4—4 of Fig. 3.

Fig. 5 is a fragmentary side elevational view of the chair with the table attachment fully stored therein.

In these views, the reference character 1 designates a chair of the type having side members 2 and 3 extending above and below the seat 4 to form arms and to also comprise portions of the chair base. The members 2 and 3 are respectively formed with similar compartments 5 and 6 opening in the front faces of such members and extending to the top, bottom, and rear portions of said members. Slidably fitted in the compartment 6 and normally occupying its rear portion is a table support 7. The upper portion of such support carries a forwardly projecting extension 8 normally occupying the front portion of the compartment 6, said extension being pivoted on the support by a vertical pin 9, being thus adapted to swing laterally when in the forwardly projected position illustrated in Fig. 1. A table member 10 has one of its end portions lapping the extension 9 and hinged thereto along the upper edge of the extension, as indicated at 11, such member being normally housed within the compartment 6 together with the support 7 and said extension. The hinge 11 adapts the table member to assume either the vertical position of Fig. 1 or the horizontal use position, best shown in Fig. 2. In such use position the table member extends between the chair arms, slightly below their top faces, the free end of such member being then usually seated on a support 12, carried by the side member 2. Such support is normally housed within the compartment 5 and is slid forwardly, as per Fig. 1, when required to seat the table member. It is to be noted that the compartment 6 must have substantially the maximum vertical extent afforded by the corresponding side member 3 in order that the table member may be accommodated in such compartment when not in use, while having adequate length to allow the described seating on the support 12. In the outer face of the support 12 are formed two recesses or pockets 13 (Figs. 3 and 4) to which access is had in the withdrawn position of said support. These recesses serve to receive writing or sewing ma-

55

terials, or other articles suited to occasionally occupy the table member.

It is desirable to afford ingress and egress to and from the chair without necessity of lowering the table member from its use position, particularly since such lowering would entail preliminary removal of any articles resting on such member. Pivotal mounting of the extension 8 on the pin 9 in conjunction with an auxiliary support 14 on said extension permits swinging of the table member as exemplified in dash lines in Fig. 2. Said auxiliary support is formed by an arm vertically pivoted at 15 on said extension and occupying the vertical plane of the extension when not in use. Said arm is positioned for use by swinging it on the pivot 15 to diverge from said extension, whereby said arm functions as a brace, affording support to the table member at a point materially spaced from the hinge 11. The arm 14 may be formed of heavy wire with an end portion upwardly inserted in the extension to form the pivot 15, the other end portion being formed with a return bend 16 as a seat for the table member. A wear plate 17 secured to the under face of the table member has a shoulder 18 engageable by the arm 14 to establish the use position of such arm.

A pair of plates 19 secured to the front faces of the chair arms sufficiently overlap the upper ends of the compartments 5 and 6 to establish forward limiting positions for the supports 12 and 7. The support 12 has a shoulder 20 at its top to engage the corresponding plate 19 and the upper end of the front face of the support 7 exercises a like function. Finishing strips 21 and 22, of any suitable material are secured respectively to the front faces of the support 12 and table member, the latter being materially reinforced by its strip 22. When the table attachment is housed in the side members 2 and 3, said strips seat against said members, covering the compartments 5 and 6.

The described attachment adds utility to any arm chair and is particularly a convenience to invalids, convalescents, or others, whose condition requires considerable occupancy of such a chair.

What I claim is:

1. In combination, a chair having arm-forming side members and a forwardly opening compartment in one such member, a table member support normally occupying the rear portion of said compartment, a forward extension from said support, normally occupying the front portion of said compartment, said support and extension being forwardly slidable in unison to dispose the extension in an exterior relation to the compartment, a table member having an end portion substantially parallel and adjacent to said extension, means hinging said end portion to the extension, establishing a substantially horizontal pivotal axis for the table member, and a support for the other end portion of the table member, carried by the other of said side members.

2. In combination, a chair having arm-forming side members and a forwardly opening compartment in each such member, a table member support normally occupying the rear portion of one of said compartments, a forward extension from said support, normally occupying the front portion of said compartment, said support and extension being forwardly slidable in unison to dispose the extension in an exterior relation to

the compartment, a table member having an end portion substantially parallel and adjacent to said extension, means hinging said end portion to the extension, establishing a substantially horizontal pivotal axis for the table member, and a support for the other end portion of the table member, normally occupying the other of said compartments and forwardly slidable to establish a seat for the last-mentioned end portion.

3. In the combination set forth in claim 2, a pair of cover members for said compartments secured respectively to the front margin of the table member and to the front end of the last-mentioned support, and normally engaging the front faces of said side members.

4. The combination set forth in claim 2, the last-mentioned support having a recess in its outer face exposed by a forward sliding of such support and receiving articles to be used on the table member.

5. In the combination set forth in claim 2, coacting stops on the side members of the chair and on the table member supports, limiting forward sliding of such supports.

6. In combination, a chair having arm-forming side members and a forwardly opening compartment in one such member, a table member support normally occupying the rear portion of said compartment, a forward extension from the front portion of said support, normally occupying the front portion of said compartment, means pivoting said extension on said support affording the extension swinging travel about a substantially vertical axis, said support and extension being forwardly slidable in unison to dispose the extension in an exterior relation to the compartment, a table member having an end portion substantially parallel and adjacent to said extension, means hinging said end portion to the extension, whereby the table member may be swung from a substantially vertical position of registration with said compartment to a substantially horizontal position of use, means carried by the other of said side members for supporting the other end portion of the table member in its position of use, and an auxiliary support for the table member carried by said extension and adjustable to engage the table member in spaced relation to said hinging means to maintain the horizontal use position of the table member when swung in unison with said extension about said vertical axis.

7. The combination set forth in claim 6, said auxiliary support comprising an arm pivoted on said extension to swing about a vertical axis from a position substantially in the vertical plane of the extension to a divergent relation to such plane.

8. The combination set forth in claim 6, said auxiliary support comprising an arm having an end portion upwardly inserted and pivotal in the extension, said arm being upwardly bent to provide a table member engaging end portion lying forwardly of the extension when out of use.

ELSIE M. RUNKLES.
